POPPET VALVE

Filed Aug. 2, 1926

FIG. 1.

FIG. 2.

INVENTOR:
RICHARD E. BISSELL
BY
A. S. Merkle
ATTORNEY.

UNITED STATES PATENT OFFICE

RICHARD E. BISSELL, OF CLEVELAND HEIGHTS, OHIO, ASSIGNOR TO THOMPSON PRODUCTS INC., OF CLEVELAND, OHIO, A CORPORATION OF OHIO

POPPET VALVE

Application filed August 2, 1926. Serial No. 126,354.

The invention relates to valves such as are employed in internal combustion engines, commonly referred to as "poppet" valves, and more particularly to exhaust valves. 5 The heat of exploded gases of internal combustion engines is very high prior to and at the time they pass the exhaust valves, and the valves are intensely heated thereby. Notwithstanding the fact that such valves are generally made of fine materials with an object to withstand high temperatures without warpage, such warpage and consequent loss of compression frequently occur. Warpage results from the fact that the valve head is 15 irregularly heated at different points, resulting in irregularity of expansion, and when expansion is greater than the elastic limit of the metal, the original form is not restored. Irregularity of heating at different points 20 of the head is of course due to the fact that some parts lie in a zone of constantly higher temperature than others, the temperature at any point being dependent upon the amount and velocity of the gas passing that point and 25 its proximity to the cooling medium.

The object of my invention is to reduce this tendency to warpage.

This object is accomplished by equalizing the temperature of the head, by means of a 30 metal insert in the head of higher heat conductivity than the main body of the head.

The relation of the metal insert to the valve head, in the preferred form of the invention is shown in the accompanying drawings, in 35 which

Figure 1 is a vertical section through a valve constructed in accordance with my invention, showing associated parts of the engine structure,

Fig. 2 is a top plan view of the valve head, and

Figure 3 is a fragmentary vertical sectional view through the head of a modified form of valve in which the insert is entirely enclosed by the body of the valve head.

In order to exemplify the principles of my invention, I have shown a valve of well-known shape. In accordance with my invention I provide such a valve head with an insert of 50 metal 1 differing in characteristics from the

main body of the head 2 in that the insert is of higher heat conductivity. The recess filled by the insert may be one in the head opening from the top face of the head, or it may be an interior cavity as shown in Figure 3 entirely surrounded by the material of the head. Various materials may be selected for the insert but I have found that a non-ferrous metal, such as bronze capable of withstanding a high temperature, serves well to 55 accomplish the object desired. It will be apparent that in such a construction the heat received at a point of high temperature will be quickly conducted to other parts of lower temperature, thereby equalizing the temperature throughout the head. 60

So far as I am aware, I am the first to devise a valve head containing an insert of metal and a process of making the same. Such a valve and a process of constructing 70 the same is disclosed and claimed broadly in my co-pending application Serial No. 126,355, filed concurrently herewith. The present application is restricted to a valve with an insert of metal such as will attain the objects 75 set out above.

While the process of fabricating the valve is fully set out in the copending application it may be here briefly described as consisting of forming a recess in the upper end 80 of the piece of metal which is to form the main body of the head, inserting the high heat conducting metal therein, and then upsetting the end in suitable dies whereby the two are flattened out and the main body of 85 the material is caused to partially or wholly surround and retain the insert within the main body of the valve-head (Figure 3).

While I have referred specifically to but one material as being suitable for the insert 90 it is obvious that many other materials are adapted to the purpose, and it is therefore to be understood that the disclosure herein is merely exemplary of the principles involved and that my invention is not confined thereto but includes all changes and modifications falling within the scope of the appended 95 claims.

What I claim is:

1. As an article of manufacture a two- 100

piece interlocked headed member comprising a stem, a head thereon and a flat insert in said head of greater heat conductivity than that of said head interlocked with said head.

2. As an article of manufacture a two-piece interlocked headed member comprising a stem, a head thereon and an insert having a relatively high rate of heat conductivity as compared with said head disposed wholly within said head including a relatively thin lateral portion extending toward the peripheral edge of said head and interlocked with the said head.

3. As a new article of manufacture, a two-piece interlocked poppet valve having a stem and a head integral therewith, said head having an irregular cavity therein, a metal insert of greater heat conductivity than the metal of said head disposed in said cavity for insuring a rapid conduction of heat from said head to said stem, while the valve is in use, said insert being bounded by thin lateral portions extending toward the periphery of said head and interlocked with said head.

25 Signed by me this 22nd day of July, 1926.
RICHARD E. BISSELL.
